UNITED STATES PATENT OFFICE.

C. ALBERT TATUM, OF NEW YORK, N. Y., ASSIGNOR TO HIMSELF AND FRANCIS M. UNDERHILL, OF SAME PLACE, JAMES WHITALL, ROBERT P. SMITH, CHARLES ROBERTS, AND WILLIAM H. NICHOLSON, OF PHILADELPHIA, PENNSYLVANIA, AND JOHN MICKLE, OF MILLVILLE, NEW JERSEY.

FASTENING FOR FRUIT-JAR CAPS, &c.

SPECIFICATION forming part of Letters Patent No. 292,286, dated January 22, 1884.

Application filed November 19, 1883. (No model.)

To all whom it may concern:

Be it known that I, C. ALBERT TATUM, a citizen of the United States, and a resident of New York city, New York, have invented certain Improvements in Fastening Devices for Caps of Fruit-Jars and other Vessels, of which the following is a specification.

My invention consists of the combination of the body and cap of a fruit-jar or other vessel with a pair of strips pivoted together adapted to the body and cap of the jar, and constructed to act upon each other in the manner herein-after set forth, the object being to tightly press the cover to the packing-ring on the mouth of the jar, and to retain it in this position.

In the accompanying drawings, Figure 1 is a vertical section of the upper portion of a fruit-jar, showing my improved device for securing the cover; Fig. 2, a perspective view, and Fig. 3 a perspective view of the fastener detached from the jar.

The jar A has in the upper edge of its mouth in the present instance an annular recess for receiving the usual packing-ring, B, on which bears the cover D, the latter being preferably made of glass.

The fastener consists of two hooked metallic strips, E E', loosely connected together by a pivot-pin, e. The shape of the hooked portions f of these strips will depend in a great measure on that of the exterior of the mouth of the jar and cover, the form of which may be materially varied without departing from the main feature of my invention. In all cases, however, the hooked portion of each strip should terminate in a lip, i, for underlapping the shoulder m on the neck of the jar. The strip E is really a lever having a short upwardly-bent arm, n, extending beyond the pivot-pin beneath the strip E', the arm being rounded or beveled at its outer end.

Before applying the fastener to the jar the two strips of metal should be adjusted to about the relative positions shown in Fig. 3, after which the strips must be turned away from each other on their pivot-pin e until they are in line, or thereabout, with each other. This

movement of the strips is resisted by the arm n, which presents an inclined or curved edge having a cam-like action on the under side of the strip E', so that in applying the necessary force to overcome the resistance presented by the arm n both strips will have an upward tendency, indicated by the arrows; but as this is resisted by the shoulder m of the jar there must necessarily be a compression of the cover on the packing B. Precisely the same result will be attained by making the arm n of the strip E straight, or nearly so, and by so bending the strip E' that it will bear with cam-like action on the said arm when the strips are turned on their pivot to secure the cover.

I prefer to make in the cover a central recess, in which the circular head t of the pivot-pin can fit freely—an arrangement which facilitates the ready adjustment of the fastener to a proper position on the cover, and at the same time tends to maintain the fastener in that position during the outward turning of the strips on the pivot-pin.

The strips should possess a slight inherent elasticity; hence I prefer to make them of steel or other hard elastic metal, so that there may be a yielding pressure on the cover.

The fastener may be readily detached from the jar and cover by first moving the strips to about the position shown in Fig. 3, and then raising the fastener at or near the pivot-pin, when its hooked ends will be free from the shoulder of the jar.

For the convenient manipulation of the fastener I form on each strip a lip, x.

I claim as my invention—

1. A cover-fastener in which a hooked strip, E, of metal, having an arm, n, is combined with and loosely pivoted to a hooked strip, E', the arm n and strip E' being constructed to act on each other, as described, when the strips are turned outward on the pivot-pin, all substantially as set forth.

2. The combination of the upper end of the jar having a shoulder, m, and the cover D, having a central recess, with the strips E E', each having a hooked end to underlap the

shoulder, and loosely connected together by a pivot-pin, the head of which is adapted to the recess of the cover, substantially as specified.

3. The combination of the top of the jar and cover with the two hooked strips loosely pivoted together and having lips *x*, as described. In testimony whereof I have signed my name

to this specification in the presence of two subscribing witnesses.

C. ALBERT TATUM.
